Primary Examiner — Richard E Chilcot

(74) Attorney, Agent, or Firm — Syncoda LLC; Feng Ma

(57) **CLAIM**

The ornamental design for a robot cleaner, as shown and described.

DESCRIPTION

1. Robot cleaner
- 1.1 : Perspective view 1
- 1.2 : Perspective view 2
- 1.3 : Front
- 1.4 : Back
- 1.5 : Top
- 1.6 : Bottom
- 1.7 : Left
- 1.8 : Right

1 Claim, 8 Drawing Sheets
